UNITED STATES PATENT OFFICE.

WALTER VON NESSEN, OF NEW YORK, N. Y., ASSIGNOR TO EFCOLITE CORPORATION, OF NEW YORK, N. Y.

DESIGN FOR A CEILING LIGHTING FIXTURE.

Application filed April 2, 1926. Serial No. 17,165. Term of patent 3½ years.

To all whom it may concern:

Be it known that I, WALTER VON NESSEN, a citizen of the German Republic, and a resident of the county of Bronx, city and State of New York, have invented a new, original, and ornamental Design for a Ceiling Lighting Fixture, of which the following is a specification, reference being had to the accompanying drawing, forming a part hereof.

In these drawings:

Figure 1 is a side elevational view of the ceiling lighting fixture, and

Figure 2 is an inverted plan view of the same, the part shown in full line outline being ornamented in the same manner as the part more fully illustrated.

I claim:

The ornamental design for a ceiling lighting fixture substantially as shown.

WALTER VON NESSEN.
